AUTOMATIC SPRINKLER

Filed June 20, 1949

FIG. 1.

UNITED STATES PATENT OFFICE

2,580,810

AUTOMATIC SPRINKLER

Howard D. Mathis, Edwardsville, Ill.

Application June 20, 1949, Serial No. 100,176

1 Claim. (Cl. 169—26)

1

This invention relates to automatic fire extinguishers, and more particularly to an extinguisher which combines in a unitary structure a chemical sprinkler system and means for setting off an alarm signal, the primary object of the invention being to produce a structure of this kind which is adapted to be mounted above a ceiling, so that all but a very small portion thereof is concealed, providing automatic protection both above and below the ceiling.

An important advantage of my invention lies in the fact that it operates automatically at either of two points to release the fire-extinguishing chemical, that is, at the bottom of the structure beneath the ceiling and at a point above the ceiling, whereas extinguishers of this general type as previously constructed operate only at the lower portion thereof. Another advantage of the invention is due to its novel mounting, which permits the bulky glass portion of the structure to be positioned above the ceiling where it will be concealed against accidental breakage, and still another feature is that the presence of the structure does not detract from the appearance of a room since, due to its position above the ceiling, it cannot be seen from the interior of the room.

In the drawings—

Fig. 1 is a cross-sectional perspective view illustrating the structure mounted above a ceiling ready for operation.

Fig. 2 is an enlarged detail view taken on line 2—2, Fig. 1, illustrating the means for securing the structure to the ceiling.

In Fig. 1 are shown a floor A, joists B, and a ceiling C, all of these parts being partly broken away and all being of ordinary construction.

To receive the fire extinguishing structure, an opening is cut into the ceiling C, and a flush plate 1 of plastic or other non-conducting material of somewhat larger diameter than said opening is mounted on the underside of the ceiling so as to close said opening, but leaving the spray nozzle (to be described later) exposed below the ceiling. A split metal ring is mounted in the opening of the ceiling C, and this ring is formed of rigid material and has an outwardly extending, corrugated, horizontal flange 2 and a downwardly extending vertical flange 3, the ring being of such dimensions that the vertical flange 3 lies against the wall of the opening which was cut in the ceiling C, as heretofore mentioned, and the horizontal, corrugated flange 2 rests upon the upper surface of said ceiling surrounding its opening. Bolts 4 extend upwardly from the flush plate 1, and locking nuts 5 of inverted U-shape are screwed down upon said bolts 4 until said nuts come into tight engagement with the corrugated flange 2 of the above-mentioned split ring, thus serving to secure the flush plate 1 and the ring 2—3 securely in position adjacent the

2

opening in the ceiling C, all of which is clearly shown in Fig. 1.

The flush plate 1 is cut out at its center, as shown at 6, and from this cut-out a rigid housing 7 of plastic or other non-conducting material depends, said housing being provided with an outwardly extending flange 8 which rests upon the upper surface of the flush plate 1 to retain the housing 7 in position. A layer of insulation 9 is positioned upon the flange 8, and a metal alarm signal contactor plate 10 rests upon the insulation 9, the plate 10 being provided with a central aperture 11. A funnel-shaped member 12 of plastic or other non-conducting material is mounted upon the plate 10, said funnel-shaped member having an out-turned flange 13 which rests upon said plate 10, and rivets 14 passing through the flange 13, plate 10, insulation 9, flange 8, and flush plate 1 secure all these parts firmly together, with the funnel-shaped member 12 in upright position as shown in Fig. 1. The contactor plate 10 is provided with apertures of larger dimensions than the rivets 14, so that the rivets may pass through said plate 10 without touching the same; or, if preferred, the walls of said apertures could be lined with non-conducting, fibrous material (not shown). A pear-shaped glass container 50 rests within the upper portion of the funnel-shaped member 12 so that its smallest part extends down into the funnel-shaped member to a point somewhat above the plate 10, and its upper portion extends upwardly beyond said funnel-shaped member. A volatile liquid L is introduced into the glass container 50, after which said container is hermetically sealed.

A bullet 15 within the housing 7 has an elongated stem 16, which extends through an aperture in the floor of the housing 7, said stem having a notch 17 in that portion thereof which extends beyond said floor. The bullet 15 is surrounded by a compressed coil spring 18, and the spring 18 is enclosed within a metal sleeve contactor 19. The sleeve 19 has a metal top closure 20 riveted thereto, the closure 20 being of greater diameter than the aperture 11 in the plate 10, and the closure 20 has a central aperture through which the upper portion of the bullet 15 protrudes. Beneath the floor of the housing 7 a pair of arms 21 engage the notch 17 of the stem of the bullet, said arms being secured against springing apart by a fuse 22, which arrangement, it will be understood, serves to hold the stem 16, and consequently the bullet 15, in the position shown in Fig. 1, compression of the spring 18 being maintained by the engagement of the arms 21 with the stem of the bullet 15.

A rigid supporting bracket 23 of plastic or other non-conducting material extends upwardly along side of but spaced slightly away from the funnel-shaped member 12, said bracket having a hori-

zontally extending flange 24 at its lower portion which is attached to the flush plate 1 by rivets 25. As will be noted from Fig. 1, that portion of the bracket 23 which extends upwardly from the flange 24 conforms approximately to the shape of the funnel-shaped member 12, and when it reaches the upper portion of said member 12 it extends outwardly for a short distance, and then terminates in an approximately vertical section 26.

A metal alarm signal contactor 27, supported by the section 26, extends to a point just clear of the glass container 50. The contactor 27 has an aperture 28 similar to the aperture 11, and within the metal contactor 27 a bullet 29 is mounted and surrounded by a compressed coil spring 30, which is enclosed by a metal sleeve 31 similar to the metal sleeve 19, the stem of the bullet 29 extending through the section 26 and being held in place by a pair of arms 32 which engage said stem to retain it in position, and the arms 29 being prevented from spreading apart by a fuse 33. From what has been said, it will be apparent that the assembly just described with respect to the retaining and releasing of the bullet 29 is similar to the assembly including the housing 7, bullet 15, and associated elements, so that more detailed description of the last-described assembly is deemed unnecessary.

A conducting wire 34 is soldered to the sleeve contactor 19 and extends upwardly, passing through a notch 35 in the contactor 19. At its upper terminal point the wire 34 is soldered to a metal element 36 which is mounted on the upper rim of the funnel-shaped member 12. Another conducting wire 37 is attached to the metal element 36 and to sleeve contactor 31. Another conducting wire 38 is attached to contactor 10 and extends to terminal 39. Another conducting wire 40 is attached to the contactor 27 and terminal 39. The terminal 39 is also mounted on the rim of the funnel-shaped member 12, and the wire 38 is soldered thereto. Conducting wires 41 and 42 attached to the metal terminals 36 and 39, respectively, lead to a source of electrical current and also to an electrically operated alarm signal, but since such alarm signal in itself and such source of current do not form a part of the present invention but may be of any appropriate type, they have not been illustrated in the drawings and will not be described. The two conductors 19 and 31 are wired in parallel, and the plate 10 and contactor 27 are also wired in parallel. Conducting wires 41 and 42 are also in series extending to the source of electrical current and the alarm signal.

In operation the procedure is as follows:

Suppose a fire starts at a point below the ceiling C. The heat of the flames will melt the fuse 22, thereby releasing the arms 21 and permitting them to spread apart, which disengages them from the notch 17 in the stem of the bullet 15. Obviously, when this restraint is removed from the bullet it relieves the pressure on the coil spring 18, so that the spring expands instantly and carries up with it with considerable force the bullet 15, and the bullet crashes through the bottom of the glass container, shattering said container and releasing the volatile liquid L, and upon contact with the air said liquid is transformed into a gas which has a fire-extinguishing quality, as is well understood.

In the event a fire should break out at a point above the ceiling, the same procedure would take place with respect to the fuse assembly in the sup-

port 23; that is to say, the fuse 33 would be melted by the heat of the fire, releasing the arms 32 and consequently the bullet 29 which, through instantaneous expanding action of the coil spring 30, 5 would shatter the glass of the container 50, and thus release the liquid therein so that it would be transformed into a fire-extinguishing gas upon contact with the heated air.

Vents V are provided in the funnel-shaped 10 member 12 and the housing 7 through which either the liquid or the gas may escape when the glass container 50 has been shattered by either or both of the bullets 15 or 29.

The alarm system operates as follows:

In the event of a fire underneath the ceiling, upon expansion of the coil spring 18 as above described it would carry upwardly with it the sleeve contactor 19. It will be remembered that this sleeve contactor has a metal closure 20 which is 20 of larger diameter than the aperture 11 in the contactor plate 10, so that said plate 10 serves as a stop for the metal closure 20. When the metal closure 20 contacts the metal contactor plate 10, it acts as a circuit closer for current through the 25 wire 34, attached to terminal 36, and through the wire 38, attached to the terminal 39, both terminals being connected, as heretofore mentioned, to an alarm signal (not shown).

Should the fire break out above the ceiling, the 30 same procedure would take place with respect to the upper assembly associated with the support 23; that is to say, the instantaneous expansion of the coil spring 30 would permit contact of the metal closure of the sleeve 31 with the contactor 35 27, and consequent flow of current through the wire 40 to the metal terminal 39, after which the first described flow of current would be reversed so that the wire 41 would set off the alarm.

I claim:

40 A fire extinguisher of fracturable material for mounting above a ceiling having an opening therein to permit the insertion therethrough of said fire extinguisher, a collapsible ring having a vertical portion and a horizontal portion, said ring being adapted to surround the opening in said ceiling, a plate covering the opening in said ceiling, bolts passing through said plate, members on said bolts for contacting said ring to securely hold said plate in position, said plate being 45 also provided with a central opening, a portion on said fire extinguisher for protruding through said opening in said plate, the main portion of said fire extinguisher being above said plate and said ceiling and means associated with said projecting end portion of said fire extinguisher for fracturing said fire extinguisher when a predetermined degree of heat prevails.
